UNITED STATES PATENT OFFICE.

WILLIAM SPARKS, OF JACKSON, MICHIGAN, ASSIGNEE TO THE SPARKS-WITHINGTON COMPANY, A CORPORATION OF MICHIGAN.

SIGNAL.

1,312,060.

Specification of Letters Patent.

Patented Aug. 5, 1919.

Application filed November 14, 1913. Serial No. 800,855.

To all whom it may concern:

Be it known that I, WILLIAM SPARKS, of Jackson, in the county of Jackson, in the State of Michigan, have invented new and useful Improvements in Signals, of which the following, taken in connection with the accompanying drawings, is a full, clear, and exact description:

This invention relates to certain improvements in signals and more particularly to mechanically operated signals of the diaphragm type, and although susceptible of many and varied uses is particularly for use in connection with automobiles, motor-boats and other moving bodies, and reference is hereby made to my co-pending application, Serial No. 844,152, which contains the broad claims to the actuating mechanism disclosed herein.

20 The primary object of the invention is to provide a signal which is mechanically operable to give an instantaneous alarm without possibility of failure and susceptible of a multiplicity of speeds, wholly within the control of the operator, for producing sounds of varying character both as to pitch and as to loudness and which may, therefore, be used as a short or long distance signal, and is adaptable to the needs of each case.

30 Another object is to produce such a signal of simple and comparatively inexpensive construction capable of forcing the vibration of the diaphragm at a sufficient speed so that it will create a note as distinguished from simply a noise or a sound.

Another object is to provide means operable from any predetermined point for forcing the vibration of the diaphragm at any one of the possible speeds desired with only 40 a slight movement of the operator.

Another object is to provide means for returning the operating means to its normal position after each movement, and to provide means allowing such return without 45 forcing diaphragm vibration.

A further object is to provide means either for varying the degree of contact of the diaphragm operating members and therefore the amplitude of the forced vibration of the 50 diaphragm, or simply as a compensation for ordinary wear.

Other objects and uses appear in the details of construction and arrangement illustrated in the accompanying drawings, in 55 which

Figure 1 is a side elevation of the signal.
Fig. 2 is a rear end elevation.

Fig. 3 is a central longitudinal, cross section with the amplifier partially broken away.

Fig. 4 is a top plan view partially in section, the amplifier being omitted.

Fig. 5 is a view of the ratchet case with its cover removed.

Fig. 6 is a view of the operating nut formed with a ratchet face.

Fig. 7 is a side elevation of one of the operating jaws engaging with the ratchet clutch.

The signal as shown comprises a diaphragm — 1 — having its marginal portion confined between the base of an amplifier — 2 — and a suitable case section — 3 — connected by screws — 4 — passed through the amplifier section — 2 — and threaded into the case section — 3 —, although this construction may be reversed or any other suitable connecting means substituted.

The base of the amplifier is obliquely disposed with respect to the plane of the diaphragm and a portion of the case section — 3 — is similarly obliquely disposed and provided with a depressed central portion — 5 — to form a diaphragm case within which the diaphragm may freely vibrate.

A cup shape casing — 6 — of slightly greater diameter than the depressed portion of the case section — 3 —, slidably engages the laterally extending circumferential flange — 7 — formed by depressing the portion — 5 — of the section — 3 — and is secured thereto by means of screws — 8 —, although any other suitable means may be substituted therefor. The casing — 6 — is provided with opposite bearings — 9 — and — 10 — preferably having conical sockets as shown for the reception of a squared conical ended shaft — 11 —.

The bearing — 9 —, as shown, may be rigidly secured to the casing — 6 — in any suitable manner as by welding. The bearing — 10 — is externally threaded for coaction with an internally threaded portion of the casing — 6 — and preferably a similar threaded relation with a reinforcing plate — 12 — positioned within the casing so that the bearing is adjustable through the casing and may be located in any of its adjusted positions by means of the nut — 13 —.

The upper portion of the shaft — 11 — is

twisted so as to form a spiral of suitable pitch so that a coating nut —14—, if held from rotation and moved along said shaft, will cause rotation of the same. For the 5 purpose of holding said nut from rotation when moved in one direction and thereby causing rotation of the shaft —11— and for allowing a return of said nut to normal position on the shaft without rotation of said 10 shaft by allowing the nut itself to rotate upon the return movement, a case —15— is provided adapted to be positioned on said shaft —11— and having a seat —16— formed concentric with the shaft opening —17— for 15 the reception of the nut —14— which has one of its faces provided with a plurality of ratchet teeth having abrupt radial faces on one side only, and adapted to engage projections or stops —18— when the ratchet is 20 turned in one direction and to freely ride over said stops when moving in the other direction.

The case —15— is provided with a suitable cover —19— secured thereto in any suitable manner and adapted to inclose the nut —14—. This nut —14— has an opening —20— of a form adapted to coöperate with the shaft —11— for transferring the direct 25 movement of the nut into a rotary movement of the shaft, and in the form shown this opening is substantially square and preferably has the planes of its inclosing faces obliquely disposed with respect to its axis to facilitate the starting of the relative 30 movement of the parts.

The case —15— is sufficiently deep to allow the nut —14— to lie in a position at which the teeth thereon will not engage the stops —18— upon the case. In other words, 40 the seat within the case is of sufficient depth or size to allow the nut —14— with the teeth thereon to move out of engagement with the stops upon the case so that the nut may freely rotate with respect to the case. When 45 the case is moved down by the operating handle, the inertia of the shaft —11— and the parts carried thereby cause the nut to move axially within the case to such a position that the teeth upon the nut come into 50 engagement with the stops upon the case to prevent rotation of the nut while the case is being moved in that direction. When the case is moved in a reverse direction, the nut drops down by gravity and the case is moved 55 axially with respect to the nut, which remains stationary, due to the inertia of the shaft, thereby disengaging the teeth upon the nut with the stops upon the case so that the nut may freely rotate within the case so 60 long as it is being moved in that direction.

The case —15—, the nut —14— and the cover —19— form a device which is herein-after termed a ratchet clutch, and for the 65 purpose of moving this clutch along the shaft —11— whereby the shaft is rotated by

the action of the nut —14—, the case —15— is provided with oppositely disposed pintles —21— and —22— suitably engaged by jaws —23— and —24— formed upon the bifurcated end —25— of an operating lever 70 —26—. The lever —26— is pivoted upon a bolt —27— supported in any suitable manner as by an angle bar —28— operably secured to the casing —6— by screws —29—.

A suitable spring —30— has its central 75 portion tensioned around the bolt —27— and its ends respectively bearing against the casing —6— and the lever —26— on the side of its pivot next the ratchet clutch, so that the spring normally tends to return the 80 lever to starting position after each operation and this return is rapid and easy by reason of the fact that the teeth upon the nut —14— slide over the stops —18— upon this return movement so that the nut itself may 85 rotate, thereby obviating the rotation of the shaft —11— and the vibration of the diaphragm as hereinafter described.

A suitable toothed or cam wheel —31— is mounted on the shaft —11— and preferably 90 has its marginal portion disposed in a plane substantially midway of the diaphragm —1— and operating through a slot —36— formed in the depressed portion —5— of the case section —3—, and its central portion 95 depressed or offset from the plane of its marginal portion, so that the cam wheel may force the vibration of the diaphragm at substantially the central point thereof, and yet the shaft —11— may have its spirally arranged portion extend somewhat more than one-half the length of the shaft so that a more extensive rotary movement may be imparted to the cam wheel than would be possible if the wheel were journaled upon the 100 central portion of the shaft —11—.

The diaphragm —1— is provided with a suitable contact member —32— coöperating with the wheel —31— to vibrate the diaphragm and this contact member is preferably externally threaded for coaction with an internally threaded bushing —33— secured to the diaphragm in any suitable manner, as by having one of its ends welded over a washer —34— and the contact member 110 115 may be adjusted toward and from the toothed wheel —31— by means of this threaded relation, and may be locked in any predetermined adjusted position by a lock nut —35—.

It will now be apparent that by reason of the relatively large size of the wheel —31— and the possibility of rapid rotation of the shaft —11— by the means disclosed, a very rapid vibration of the diaphragm may be 125 forced and that said forced vibration may continue for any desired space of time, limited solely by the possible extent of movement of the operating nut —14— along the shaft —11—, and that this forced vibration 130

may be repeated at frequent intervals by reason of the rapid, free and automatic return of the nut 14 to normal starting position after each operation.

Although I have shown the wheel 21 to be of substantially the same diameter as the internal diameter of the casing 20, yet it may be of any desired diameter and the cam projections thereon may be of any desired size and number and may have any relative arrangement and shape, and that the central portion of said wheel may be dished or not, at will, and that the signal may be constructed for either hand or foot operation or may be operated from any predetermined point by means of suitable connections, and that many changes may be made in the details of construction, arrangement and operation without departing from the spirit of this invention as set forth in the appended claims.

What I claim is:

1. A signal comprising a diaphragm, a resonator at the front of the diaphragm, a casing at the rear of the diaphragm, a shaft within the casing and rotatably mounted in substantial parallelism with the diaphragm, a diaphragm actuator mounted upon the shaft and rotating with the shaft and in a plane substantially perpendicular to the diaphragm and adapted to coat with the diaphragm to force vibration of the latter as the former is rotated, a nut movable longitudinally of said shaft, a handle having a portion disposed outside the casing and another portion within the casing and adapted to move said nut longitudinally of the shaft, means for holding the nut from rotation when moved longitudinally in one direction whereby the shaft is rotated and allowing free rotation of the nut when moved in a reverse direction whereby the shaft may remain stationary, and spring means supported independent of the diaphragm actuator for effecting such reverse movement without materially decreasing the momentum of said actuator.
2. A signal comprising a diaphragm, a casing, a shaft rotatably mounted within the casing, a diaphragm actuator mounted upon the shaft and rotating therewith and adapted to coat with the diaphragm to force vibration of the latter as the former is rotated, an operating member movable longitudinally of said shaft, said operating member and said shaft having cooperating parts so formed and arranged that longitudinal movement of said member forces relative rotation of said shaft and member, and means for holding said member from rotation when moved in one direction whereby rotation of said shaft is forced, and allowing rotation of said member when moved in a reverse direction whereby the shaft may remain stationary, and spring means support-

ed independent of the diaphragm actuator for effecting such reverse movement without materially decreasing the momentum of said actuator.

3. A signal comprising a diaphragm, a casing, a shaft rotatably mounted within the casing, a diaphragm actuating member having a toothed portion disposed substantially diametrically of the diaphragm and another portion mounted on the said shaft and adapted to actuate the first-named portion and disposed, in a plane at one side of the toothed portion, an operating member movable longitudinally of said shaft to force relative rotation of said shaft and member, said operating member movable into the plane of the toothed portion of the actuator, means for holding the said operating member from rotation when moved in one direction along the shaft, whereby the shaft is rotated, and allowing rotation of the member when moved in the other direction whereby the shaft may remain stationary, and spring means supported independently of the diaphragm actuating member for effecting said last-named movement without materially decreasing the momentum of the diaphragm actuating member.

4. In a signaling device, a diaphragm, a rotary actuator for vibrating said diaphragm, a spiral shaft upon which said actuator is mounted, a shaft actuator, a member adapted to move the shaft actuator along the shaft, and normally spaced parts on the shaft actuator and said member adapted to interengage upon movement of said shaft actuator in one direction.

5. In a signaling device, a diaphragm, a rotary actuator for vibrating said diaphragm, a spiral shaft upon which said actuator is mounted, a shaft actuator, a casing carrying the shaft actuator, and normally spaced parts on the shaft actuator and said casing adapted to interengage upon movement of said casing in one direction.

6. In a signaling device, a diaphragm, a rotary actuator for vibrating said diaphragm, a spiral shaft upon which said actuator is mounted, a shaft actuator, a casing carrying the shaft actuator, normally spaced parts on the shaft actuator and said casing adapted to interengage upon movement of said casing in one direction, and a handle for moving said casing lengthwise of the shaft.

7. In a signaling device, a diaphragm, a rotary actuator for vibrating said diaphragm, a spiral shaft upon which said actuator is mounted, a shaft actuator, a casing carrying the shaft actuator, normally spaced parts on the shaft actuator and said casing adapted to interengage upon movement of said casing in one direction, a handle for moving said casing lengthwise of the shaft, and spring means operating directly

upon the handle for returning the actuating parts to starting position after each shaft rotating movement without materially decreasing the momentum of the rotary actuator.

8. In a signaling device, a diaphragm, a rotary actuator for vibrating said diaphragm, a spiral shaft upon which said actuator is mounted, a shaft actuator, a member for moving the shaft actuator along the shaft, said shaft actuator and said member having a limited movement relatively to each other in a direction axially of the shaft, and clutch devices in connection with the shaft actuator and said member adapted to interengage upon movement of said member in one direction axially of the shaft and to be disengaged upon movement of said member in a reverse direction along said shaft.
- 10 9. In a signaling device, a casing, a diaphragm, a diaphragm actuator, a shaft upon which said actuator is mounted, said shaft formed with a spirally disposed pathway and having its ends supported from said casing, a member movable longitudinally of the shaft for rotating the same, said member having pintles projecting from spaced portions thereof, said casing provided with an elongated slot and a handle pivotally supported from the casing and having one end projecting outwardly through said slot, and its other end formed in a yoke, the arms of said yoke provided with jaws for engaging the respective pintles for moving said member along the shaft as the said handle is rocked about its pivot.
- 10 10. In a signaling device, a casing, a diaphragm, a diaphragm actuator, a shaft upon which said actuator is mounted, said shaft formed with a spirally disposed pathway and having its ends supported from said casing, a member movable longitudinally of the shaft for rotating the same, said member having pintles projecting from spaced portions thereof, said casing provided with an elongated slot and a handle pivotally supported from the casing and having one end projecting outwardly through said slot, and its other end formed in a yoke, the arms of said yoke provided with jaws for engaging the respective pintles for moving said member along the shaft as the said handle is rocked about its pivot, and means for returning the handle and thereby the said member to starting position after each rocking movement.
- 10 11. A mechanical horn comprising a shaft having a fixed striker and a worm groove, a diaphragm over which the striker is adapted to operate, a yieldingly supported member having a flange, a clutch device coacting with the groove, and supported by said flange, a clutch device carried by the member and spaced from the first device normally and adapted to fixedly engage with

said first device on movement of the member toward the striker.

12. In a signaling device, a diaphragm, a rotary actuator for vibrating said diaphragm, a spiral shaft upon which said actuator is mounted, a shaft actuator, a member for moving the shaft actuator along the shaft, said shaft actuator and said member having a limited movement relatively to each other in a direction axially of the shaft, and clutch devices in connection with the shaft actuator and said member adapted to interengage upon movement of said member in one direction axially of the shaft and to be disengaged upon movement of said member in a reverse direction along said shaft, pintles upon opposite sides of said member, a lever pivotally carried by the casing and having a pair of open-sided jaws engaging the pintles on said member.

85

13. In a signaling device, a diaphragm, a rotary actuator for vibrating said diaphragm, a spiral shaft upon which said actuator is mounted, a shaft actuator, a member for moving the shaft actuator along the shaft, said shaft actuator and said member having a limited movement relatively to each other in a direction axially of the shaft, and clutch devices in connection with the shaft actuator and said member adapted to interengage upon movement of said member in one direction axially of the shaft and to be disengaged upon movement of said member in a reverse direction along said shaft, pintles upon opposite sides of said member, a lever pivotally carried by the casing and having a pair of open-sided jaws engaging the pintles on said member, a spring having one end engaged with the casing and its intermediate portion engaged with the pivot of the lever, and its opposite end engaged with the lever for restoring the handle to a normal starting position after each operation in the reverse direction.

100

105

110

115

120

14. In a signaling device, a diaphragm, a rotary actuator for vibrating said diaphragm, a spiral shaft upon which said actuator is mounted, a shaft actuator, a casing substantially inclosing the shaft actuator and adapted for moving said shaft actuator along the shaft, said shaft actuator having a limited movement within the casing in a direction axially of the shaft, clutch devices in connection with the shaft actuator and said member adapted to interengage upon movement of said member in one direction axially of the shaft and to be disengaged upon movement of said member in a reverse direction along the shaft.

15. A signal comprising a diaphragm, a resonator at the front of the diaphragm, a casing at the rear of the diaphragm, a shaft within the casing and rotatably mounted in substantial parallelism with the diaphragm, a diaphragm actuator mounted upon the

125

130

shaft and rotating with the shaft and in a plane substantially perpendicular to the diaphragm and adapted to coact with the diaphragm to force vibration of the latter as the former is rotated, a nut movable longitudinally of said shaft, a pivoted handle having a portion disposed outside the casing and another portion within the casing and adapted to move said nut longitudinally of the shaft, means for holding the nut from rotation when moved longitudinally in one direction whereby the shaft is rotated and allowing free rotation of the nut when moved in a reverse direction whereby the shaft may remain stationary, and a spring having one end supported by the casing and its intermediate portion wrapped around the pivot of the lever and its opposite end engaged with the lever for effecting such reverse movement without materially decreasing the momentum of said actuator.

In witness whereof I have hereunto set my hand this 12th day of November, 1913.

WILLIAM SPARKS.
